CLAIM

The ornamental design for a vision sensor, as shown and described.

DESCRIPTION

FIG. 1 is a top, front and left side perspective view of a vision sensor according to the present invention;

FIG. 2 is a front view of the vision sensor depicted in FIG. 1; FIG. 3 is a left view of the vision sensor depicted in FIG. 1; FIG. 4 is a right view of the vision sensor depicted in FIG. 1; FIG. 5 is a back view of the vision sensor depicted in FIG. 1; FIG. 6 is an enlarged top view of the vision sensor depicted in FIG. 1;

FIG. 7 is an enlarged bottom view of the vision sensor depicted in FIG. 1; and,

FIG. 8 is a front/bottom and left side perspective of FIG. 1.
